UNITED STATES PATENT OFFICE.

THEOPHILE BERLIZE, OF BRUSSELS, BELGIUM.

EXPLOSION-MOTOR.

1,151,654.

Specification of Letters Patent. Patented Aug. 31, 1915.

Application filed August 17, 1911. Serial No. 044,675.

To all whom it may concern:

Be it known that I, THEOPHILE BERLIZE, a subject of the King of Belgium, residing at Brussels, Belgium, have invented new and useful Improvements in Combustion or Explosion Motors, of which the following is a specification.

The present invention consists in a double valve for admitting the gases into the cylinders of explosion or combustion motors.

The object of the invention is to construct a valve which is protected against the objectionable influence of the differences of expansion and with which a given diameter and lift provides an area of admission much larger than the valves hitherto constructed, the gases being admitted in the form of an annular gaseous body, which, in spite of the employment of a number of seats, enters the cylinder abruptly, driving the exploded gases before it. This valve is characterized essentially by the arrangement of a pair of superimposed valves or, more correctly, a ring and a valve superimposed, which are operated simultaneously.

In the practical carrying out of the invention the valve has two disks (or more correctly a disk and a ring) opening, rapidly and simultaneously, the opening of one of the disks which is effected by a suitable pusher, causing at the same time the actuating of a second disk which is then opened by the action of an oscillating device that moves with the first disk but is held at one of its ends on a fixed stop or abutment.

The valve that constitutes the invention is of course applicable to any combustion or exploding motor. Later on a description will be given of its application to a two-stroke cycle motor in which the explosive mixture is compressed in the gear casing.

Figure 1 is a front view of the motor being a section through the column traversed by the gases and through the admission valve, the arrows indicating the course taken by the gases. Fig. 2 is a section on a larger scale showing separately the arrangement of the valve. Fig. 3 is a similar view to Fig. 2 showing the valves in the open position. Figs. 4 and 5 are two views of modifications of details which may be employed in the construction of this valve.

The motor shown in Fig. 1 comprises the usual internal combustion engine having a cylinder and a piston which are actuated in the usual manner, the cylinder being

provided with an opening in which a valve 6 is positioned to admit the fresh gases to the same. The crank casing 7 acts as a pump body. The gases flow through a valve 11 into a column 12 which also serves for conveying the fresh gases into the crank casing and for forcing these gases into the cylinder.

The valve 6 is constructed as particularly shown in Figs. 2 and 3. It comprises a ring 14 resting on the valve seating 15 arranged in the ordinary manner on the valve case 16. This ring 14 acts at the same time as seat for the disk 6'. Openings 17 are formed in the ring 14 for the passage of the air or of the gases. The disk 6' is subjected to the action of a spring 18, which in this case is a spiral spring and bears on the one hand on the end 14 of the sleeve 19 and on the other hand against a nut 20 fixed on the end of the spindle of the disk 6'. On the sleeve 19 a dished piece 21 is mounted against which rests the spring 22 of the valve 14, which spring bears also against a dished part 23. The piece 21 carries a lug 24 to which a tumbler or rocking device 25 is pivotally mounted which bears against a fixed part 26, either directly as shown in Fig. 2, or through the medium of an ordinary connecting rod 27 (Fig. 4) or a forked rod 28 (Fig. 5) or a rod of any other suitable form. This tumbler 25 leaves between its free end and the end of the spindle of the valve disk 6' a slight play sufficient for enabling this valve disk to rest on its seat.

The valve acts in the following manner: A pusher 29 acting on the sleeve 19 through the medium of the dished part 21 forces the ring 14 to descend and to carry with it the part 21, the sleeve 19, the spring 18 and the disk 6'. The tumbler 25 likewise descends as a consequence. However, as it is sustained at one of its ends in the fixed part 26, it is inclined and depresses the disk 6', thus instantly doubling the area of passage. The pusher 29 has this peculiarity that it forms for itself a counter-valve for preventing the leakages which might arise in consequence of prolonged use. For this purpose, the pusher has at its base a seat 30 that bears against a rim 31 forming a seat in the cover 32 that closes the cup containing the valve. In the bottom of the pusher a recess 33 is formed for the passage of the tumbler. A spring 34 presses the seat 30 of the pusher continually against the seat 31 of the cover

of the valve. The chamber in which the valve is placed is not in direct communication with the crank casing. It is only supplied as a consequence of the leakages passing through the rods of the valves and a pressure is created there which is sensibly less than the pressure that prevails in the crank-casing.

It may be observed that the valve described is sheltered from the leakages that may arise from unequal expansion and that the disk 6' travels at twice the speed of the ring 14. The consequence is, that even with a large area of opening, the effects of inertia, frequent causes of breakage of the valve and of disturbances in the distribution are obviated. Moreover, owing to the fact that the opening is effected at the periphery of the cylinder, the fresh gases are admitted into the cylinder in the form of an annular cylindrical sheet, so that the abrupt entrance of this gaseous body into the cylinder causes a rapid driving in of fresh gases reducing to the minimum the chances of these gases being mixed with the exploded gases.

What I claim is:

1. In a double inlet valve for the admission of the gases into the cylinders of explosion motors the combination of a valve-case having an inlet port, a ring seating upon said inlet port, a disk seating upon said ring, a pusher causing the opening of the ring and means controlled by the move-

ment of the ring toward its open position, 35 for moving said disk to its open position.

2. In a double inlet valve for the admission of the gases into the cylinders of explosion motors the combination of a valve-case having an inlet port, a ring seating 40 upon said inlet port, a disk seating upon said ring, a pusher actuating said ring, a rocking device moving with said ring and adapted to act upon the disk and a fixed stop for said rocking device, whereby the 45 opening of the ring causes at the same time the actuating of the disk.

3. In a double inlet valve for the admission of the gases into the cylinders of explosion motors, the combination of a valve 50 case having an inlet port, a ring seating upon said inlet port, a disk seating upon said ring, a rocking device moving with the ring and adapted to act upon the disk, a fixed stop for said rocking device, whereby 55 the opening of the ring causes at the same time the actuating of the disk, a pusher actuating the ring, a valve provided on said pusher, a seat in the valve-cage for said valve and a spring for returning said valve 60 to its seat.

In testimony whereof I have signed my name to this specification in the presence of two subscribing witnesses.

THEOPHILE BERLIZE.
